UNITED STATES PATENT OFFICE.

HENRY B. BARDEN, OF WALLINGFORD, VERMONT, AND CLIFFORD A. BARDEN, OF WABASH, INDIANA.

PROCESS FOR MAKING TOOLS.

1,220,060.

Specification of Letters Patent. Patented Mar. 20, 1917.

Original application filed November 19, 1914; Serial No. 872,926. Divided and this application filed April 6, 1916. Serial No. 89,259.

To all whom it may concern:

Be it known that we, HENRY B. BARDEN, a citizen of the United States, residing at Wallingford, in the county of Rutland and 5 State of Vermont, and CLIFFORD A. BARDEN, a citizen of the United States, residing at Wabash, in the county of Wabash and State of Indiana, have invented new and useful 10 Improvements in Processes for Making Tools, of which the following is a specification.

This invention relates to an improvement in processes for making tools and more particularly to hoes, shovels or similar implements, involving the subject matter which 15 was divided out from our co-pending application, Ser. No. 872,926, filed November 19, 1914.

The object of the present invention is to 20 provide a process for constructing implements of the nature set forth whereby the cost of production may be substantially reduced and incidentally an implement of 25 great strength and durability result therefrom.

The invention consists of the several steps and operations substantially set forth in the following specification and particularly pointed out in the claims.

30 Referring to the drawings:

Figure 1 illustrates a side elevation of a strip of metal preferably embodying the initial step in the construction of an implement.

35 Fig. 2 is an end elevation of the strip illustrated in Fig. 1.

Fig. 3 is a detail view of the strip illustrating the second operation as having taken place.

40 Fig. 4 is a front elevation of a hoe in the course of construction and substantially embodies the operation following that illustrated in Fig. 3.

Fig. 5 is a side elevation of the completed 45 work member of a hoe.

Fig. 6 is a perspective view of a shovel constructed in accordance with the process embodying this invention.

Like numerals refer to like parts in all 50 views of the drawings.

In the drawings, 8 illustrates a strip of metal having an enlargement or rib 9 arranged longitudinally of said strip and substantially at the center thereof, said rib be-

ing of any preferred conformation but 55 preferably convexly curved as illustrated in Fig. 2, and disposed substantially symmetrical with respect to the opposite faces 10 and 11 of said strip.

The strip embodying the construction re- 60 cited may be and preferably is formed between suitable rollers in the manner well known to those skilled in the art. The dimensions of said strip and said rib may be varied in accordance with the implement for 65 which the same is intended. For instance, if it is intended for a hoe, as illustrated in Figs. 4 and 5, the width of said strip, from the edge 12 to the edge 13 thereof, which is somewhat thicker than the finished hoe will 70 be made, is made somewhat narrower than the work member 14 of said hoe and likewise the length of the strip 8 will be substantially shorter than the combined length 75 of the work member 14 and the finished shank 15 of said hoe.

The next step in the construction of a hoe is preferably to remove predetermined portions of the material constituting said strip upon opposite sides of and contiguous to 80 said rib 9. The portions just referred to will be indicated by the notches 16 and 17 in Fig. 3, thereby leaving a portion 18 of said rib 9 extending beyond the remaining portion of the strip 8, which remaining portion constitutes the material from which the work member of the implement is to be formed and the portion 18 constitutes the material from which the shank of the implement will 85 be formed.

The next step in the operation of forming a hoe is to forge the material into a shape as near like the finished work member is to be, as possible, after which said work member is finished off in the manner desired. During the forging of said work member the remaining portion of the strip 8 on opposite sides of the rib 9 is worked out together with said rib portion contiguous thereto so as to provide a working edge at 19 of substantially 100 equal thickness throughout while at the rear edge of said work member the rib still retains a greater portion of its previous dimension as at 20. The portion 18 of the rib 9 is also forged and drawn out by reducing the 105 size thereof to the length necessary for the finished shank as will be seen in Fig. 4, said rib being slightly tapered after which said

shank may be bent to the desired angle with relation to the work member, that is, if the implement is to be formed into a hoe the shank will be bent substantially as indicated 5 in Fig. 5, extending at right angles to the work member 14.

If it is desired to make a shovel, as illustrated in Fig. 6, instead of a hoe, the process will be substantially identical with that 10 hereinbefore set forth up to and including the form shown in Fig. 3.

The next step, however, in this form of implement consists in forming the work member 21 of the shovel substantially as was 15 the work member of the hoe, but the portion 18 of the rib instead of being drawn out as was the one illustrated in Fig. 4, may be split as indicated by the line *a—a* Fig. 2, from the extremity 22 of said member to the juncture 20 23 of said member 18 with the work member 14 and forming forward and rear portions 24 and 25 respectively.

These portions 24 and 25 are then forged 25 into a suitable shape, preferably as indicated in Fig. 6 to form a socket 26 into which the handle of the shovel, not shown in the drawings, may be inserted and secured.

In an implement formed in accordance 30 with the above described process, the weak points so often present in implements formed by welding the work member and shank together from separate pieces of material will be entirely eliminated owing to the fact that the shank and work member in the present 35 implement are formed from a single piece of material requiring no welding whatever in any part of its construction.

The advantages resulting from the construction hereinbefore described consist in 40 the formation of a very strong, durable implement with the expenditure of a very small

amount of labor. The blanks, having an enlargement extending longitudinally through the center thereof, are all formed preferably by rolling which is the simplest method of 45 forming material of this nature. This leaves a very large center portion from which the shank of the tool may be constructed, while the portion adjoining said enlargement is very much thinner and requires only a very 50 small amount of hammering or forging to reduce it to the proper thickness desired for the tube.

Having thus described our invention what we claim and desire by Letters Patent to secure is:

1. A process for making tools which consists in forming a strip of metal with an enlargement extending longitudinally through the center thereof and disposed substantially symmetrical with respect to opposite faces of said strip, then in removing predetermined portions of the material constituting said strip upon opposite sides of and contiguous to said enlargement, and in 65 subsequently forging the remaining portions of said strip into the form desired.

2. A process for making tools which consists in forming a strip of metal with a rib extending longitudinally substantially 70 through the center thereof, then in removing predetermined portions of the material constituting said strip upon opposite sides of and contiguous to said rib, and then in forging the portion of said rib which was 75 contiguous to the removed portions of said strip into a shank and the remaining portion of said strip into a work member.

In testimony whereof we have hereunto set our hands.

HENRY B. BARDEN.
CLIFFORD A. BARDEN.
